FLUID PRESSURE OPERATED APPARATUS

Ion Ven Kert Hott, Dayton, Ohio, assignor to The Joyce-Cridland Company, Dayton, Ohio, a corporation of Ohio

Application March 29, 1939, Serial No. 264,821

28 Claims. (Cl. 60—51)

This invention relates to a fluid pressure operated apparatus and more particularly to an apparatus provided with means for recovering and utilizing air under pressure which is ordinarily wasted. In various types of air operated apparatus the air remains under pressure in a work receptacle after the work has been performed, and the present apparatus is designed to recover that air without substantial loss of pressure and return it to the compressor where it is further compressed for subsequent use. The present application is a continuation in part of my application for patent Serial No. 195,113, filed March 10, 1938, and now abandoned, in which there is shown and described one form of apparatus for accomplishing this result. The present apparatus is in the nature of an improvement on and further development of the apparatus there shown.

One object of the invention is to provide such an apparatus with improved means for controlling the operation thereof.

A further object of the invention is to provide such an apparatus having means for connecting the air space in the work receptacle with the compressor substantially simultaneously with the interruption of the supply of air under pressure to the work receptacle.

A further object of the invention is to provide a hydro-pneumatic lift having a unitary device for controlling the raising and lowering of the ram and the return of the air under pressure to the compressor.

A further object of the invention is to provide such a lift with means whereby air under pressure may be withdrawn from the work receptacle either prior to or during the lowering of the ram.

Other objects of the invention may appear as the apparatus is described in detail.

In the accompanying drawings Fig. 1 is a front elevation of an installation embodying the present invention, omitting the lifting mechanism per se; Fig. 2 is a front elevation of the compressor, storage reservoir, work receptacle and controlling mechanism; Fig. 3 is a side elevation of the valves and their controlling mechanism; Fig. 4 is a schematic view of an installation embodying the invention; Fig. 5 is an elevation of the main valve unit; Fig. 6 is a section taken through the liquid valve on the line 6—6 of Fig. 5; Fig. 7 is a section taken on the line 7—7 of Fig. 5; Fig. 8 is a section through the supply and exhaust valves taken on the line 8—8 of Fig. 5; Fig. 9 is a detail view of a portion of the actuating device showing one pair of cams; Fig. 10 is a side elevation of a check valve between the compressor and the air reser-

voir; Fig. 11 is a section taken on the line 11—11 of Fig. 10; Fig. 12 is a sectional view of the return valve unit; Fig. 13 is a section taken on the line 13—13 of Fig. 12; Fig. 14 is a sectional view of the relief valve for the compressor; Fig. 15 is an elevation of the valve of Fig. 14; and Fig. 16 is a rear elevation of the actuating device.

In these drawings I have illustrated one embodiment of the invention and have shown the same as applied to a hydro-pneumatic automobile lift of a known type. It will be understood, however, that this embodiment has been chosen for the purpose of illustration and that the mechanism may take various forms and may be applied to fluid operated apparatus of various kinds.

The operation of the apparatus can best be understood by reference to the schematic view of Fig. 4. As there shown, the lift comprises a vertical cylinder 20, preferably sunk in the ground, and a ram 21 mounted in said cylinder and provided at its upper end with a load supporting structure, a portion of which is shown at 22. The cylinder 20 is connected by a conduit 23 with a receptacle 24 for the oil or other liquid propellant which is utilized in the operation of the lift. The liquid propellant is forced from the receptacle 24, which may be characterized as the work receptacle, by air under pressure admitted to the upper portion thereof through a supply conduit which is connected with an air compressor 25 and constitutes a discharge line therefor. This compressor may be of any suitable character and may be operated in any suitable manner, as by means of an electric motor 26. In the arrangement here shown the supply conduit comprises a pipe 27 leading from the outlet 28 of the compressor to a valve casing 29, a pipe 30 leading from the valve casing and connected with a pipe 31 leading to the air space in the upper portion of the work receptacle 24. The pipe 27 is provided with a branch pipe 32 leading to an air storage reservoir 33 in which air under pressure is stored for use, a check valve 34 being interposed in the pipe 27 between the branch pipe 32 and the compressor to prevent the reverse flow of air when the compressor is not in operation. The flow of air through the valve chamber 29, from the pipe 27 to the pipe 30, is controlled by a supply valve 35 which is preferably so arranged that it will be held to its seat by air pressure. In the present instance this valve is provided with a stem 36 which projects beyond the wall of the casing for engagement by an actuating device. The flow of liquid from the work receptacle to the lift is controlled by a

valve 31 here shown as a gate valve having a stem 38 arranged for engagement by an actuating device. When the valves 35 and 37 are open air under pressure will be supplied from the compressor through the pipe 27, valve casing 29, pipes 30 and 31 to the work receptacle 24 and the liquid will be forced from the work receptacle through the conduit 23 to the lift cylinder 20, thereby elevating the ram and the load thereon. When the load has been elevated the supply valve 35 is closed to interrupt the supply of air under pressure to the work receptacle and the liquid valve 37 is closed to retain the ram in its elevated position.

After the supply of air to the work receptacle has been interrupted a substantial quantity of air under pressure will be retained in the air space in the upper end of the work receptacle. In order to recover this air under pressure the work receptacle is connected by a suitable conduit with the intake 39 of the air compressor, thereby supplying air to the compressor under pressure and enabling such air to be again raised to working pressure by a relatively short operation of the compressor. The return conduit leading from the work receptacle to the compressor may be of any suitable character and for the sake of simplicity of construction I have utilized the pipe 31, which forms part of the supply conduit, as a part of the return conduit and have provided the pipe 30 with an extension 40 with which the pipe 31 communicates. The pipe 40 is connected with an inlet pipe 41 leading to the intake of the compressor and the connection between the pipe 40 and the pipe 41 is controlled by a return valve.

In the present construction this return valve forms a part of the valve unit comprising a single casing 42 having a return valve chamber 43 in which is mounted a valve 44 to control the passage of air from the pipe 40 to the pipe 41. This valve is so arranged that it will be held in its closed position by air pressure in the pipe 40 but it may, if desired, be provided with a spring to initially close the same. A fluid pressure operated device is provided for opening the valve 44 and for this purpose the valve casing 42 is provided with a small cylinder 45 into which the stem of the valve 44 extends and in which that stem is provided with a piston 46 preferably having a pressure area slightly greater than the area of the valve 44. The cylinder 45 of the pressure operated device is connected by a tube 47 with a suitable source of supply for air under pressure. Preferably the tube is connected with the supply conduit and, as here shown, it leads to a valve chamber 48 in the main valve casing 29.

The admission of air to the valve chamber 48, and therefore to the cylinder 45 of the pressure operated device, is controlled by a valve 49 which preferably has a part extending beyond the wall of the main valve casing for engagement by an actuating device. When the valve 49 is in one position a port 50 is open to connect the valve chamber 48 with the interior of the main valve casing 29. When the valve 49 is in another position the port 50 will be closed and a relief port 51 will be opened to vent the valve chamber 48 and thereby relieve the pressure on the piston 46 of the pressure operated device. When the supply valve 35 is opened the valve 49 will be moved to a position to vent the supplemental chamber 48, and a portion of the air which passes through the valve chamber 29 will pass

through the pipe 40 into the chamber 43 and close the return valve 44. Thereafter all the air passing through the valve chamber 49 will pass to the work receptacle. When the valve 35 is closed the valve 49 is moved to a position to connect the supplemental chamber 48 and the pressure operated device 46 with the valve chamber 29 and the pressure of the air in the work receptacle will be transmitted through the pipes 31 and 30 to the air in the valve casing 29 and a portion of this air will pass through the supplemental chamber 48 to the pressure operated device 46 and open the valve 44. That valve at this time will be subject to the pressure of the air from the work receptacle but the piston 46 is of an area sufficiently large to open the valve, thus permitting air under pressure from the work receptacle to flow to the intake of the compressor, if the latter is in operation, and this air will be further compressed and discharged from the compressor to the reservoir 33. When the apparatus is idle the air reservoir 33 usually contains air under pressure to initiate the movement of the ram 21 but air from the reservoir is not always sufficient to complete the movement of the lift and as the pressure in the reservoir falls the operation of the compressor will be initiated, by a pressure controlled device herein-after described, and will thereafter deliver air directly from the compressor to the work receptacle without passing through the reservoir. When the operation of the lift has been completed and the supply of air to the work receptacle has been interrupted the compressor will usually operate for a substantial period of time to restore the pressure in the air reservoir 33. It is during this period of operation that it is preferred to return the air from the work receptacle to the compressor.

When the return valve 44 is closed the intake of the compressor is connected with the atmosphere or other source of low pressure air and, as here shown, the inlet pipe 41 is connected through the valve casing 42 with a short pipe 52 which is in open communication with the atmosphere, a check valve 53 being interposed between the pipes 41 and 52 and so arranged that it will be closed by back pressure in the pipe 41 or by return air entering that pipe from the valve chamber 43.

The air is usually returned from the work receptacle 24 to the compressor 25 while the liquid valve 37 is closed to retain the ram in its elevated position. When this valve is opened to permit the lowering of the ram the liquid will be forced from the lift cylinder 20 through the pipe 23 to the work receptacle and the air which remains in the work receptacle, at low pressure, must be permitted to escape therefrom. For this purpose the valve casing 29 is provided with a second supplemental chamber 54 which is connected with a pipe 55 leading to the atmosphere, this pipe being in the present instance connected with the pipe 52 through which atmospheric air is supplied to the compressor. The connection between the supplemental chamber 54 and the interior of the valve casing 29 is controlled by a valve 56 so arranged that it will be held in its closed position by pressure in the valve casing and, in the present instance, having a valve stem 57 extending beyond the wall of the valve casing for engagement by an actuating device. When the liquid valve 37 is opened to lower the lift the valve 56 will also be opened, thereby permitting air to flow from the work receptacle

through pipes 31 and 30 to the valve chamber 29 and thence through the supplemental chamber 54 and pipe 55 to the atmosphere. This air is under low pressure and if the compressor is in operation it will pass the check valve 53 to the inlet pipe 41 and the compressor.

The several valves associated with the valve casing 29 may be manipulated in any suitable manner to control the operation of the apparatus but I prefer to provide a unitary actuating device which will actuate the valves at the proper times and in the proper sequence. As here shown, that actuating device comprises a member 58 having movement in two directions and it is provided with cam surfaces 59 and 60 arranged to engage respectively the stem 36 of the valve 35 and the stem 57 of the valve 56. These cam surfaces are so arranged that when the member 58 is in its intermediate or neutral position both valves will be closed and the movement of the member 58 in one direction from its neutral position will open the supply valve 35 and its movement in the other direction from its neutral position will open the exhaust valve 56. The member 58 is also provided with cam surfaces 61 and 62 so arranged with relation to the part 38 of the liquid valve that when the member 58 is in its neutral position the liquid valve will be closed but will be moved to its open position by the movement of the actuating member 58 in either direction from its neutral position. The actuating member is also provided with other cam surfaces 63 and 64 so arranged with relation to the valve 49 that when the actuating member 58 is in its neutral position the valve 49 will be in a position to connect the valve casing 29 with the supplemental chamber 48 and the pressure operated device 46. When the actuating member 58 is moved in either direction the connection between the valve casing and the supplemental chamber will be interrupted and the port 51 will be opened to vent the valve chamber 48. Thus it will be apparent that when the lift is to be elevated the actuating member 58 is moved in a direction which will open the supply valve 35 and will substantially simultaneously open the liquid valve 37 and actuate the valve 49 to interrupt the connection between the valve casing and the supplemental valve chamber 48, thus permitting the return valve 44 to close. When the elevation of the lift has been completed the actuating member 58 is returned to its initial position, thereby causing the supply valve 35 and the liquid valve 37 to be closed and the valve 49 to be moved to a position to open the port 50 and connect the valve casing with the pressure operated device 46, thus causing the return valve to be opened to permit air under pressure to pass from the work receptacle to the compressor, provided the compressor is operating, as will be described. When the lift is to be lowered the actuating member is moved in the other direction, that is, in a direction to open the exhaust valve 56 and this movement will also open the liquid valve 37 to permit the liquid to flow from the lift cylinder to the work receptacle and will move the valve 49 to a position to interrupt the connection between the supplemental chamber 48 and the valve casing and to vent the supplemental chamber, thereby permitting the return valve to close.

The means for controlling the operation of the compressor to normally maintain a predetermined pressure in the air reservoir 33 may be of any suitable character and is here shown as substantially similar to the pressure controlling

mechanism of the above mentioned application. Briefly it comprises a switch lever 65 pivotally mounted at 66 and provided with a resilient contact 67a to bridge stationary contacts 68 in the circuit of the motor 26. This lever is provided with a laterally extending portion having a tapered nose 67 with which cooperates a tapered plunger 69 slidably mounted on a lever 71 pivotally mounted at 70. The movement of the plunger 69 in one direction about the axis 70 will cause it to be depressed against the action of a spring 71a and to pass the nose 67, the spring then causing the plunger to contact with the opposite face of the nose 67 and move the switch 65 to its open position. When the plunger is moved in the other direction, from the last mentioned position, the plunger will engage the other face of the nose 67 and move the lever in a direction to close the switch. The lever 71 which carries the plunger 69 is connected by a rod 72 with a diaphragm 73 in a closed casing 74 and a spring 75 acts on the rod 72 to hold the plunger 69 normally in a position to close the switch. The casing 74 is connected on that side of the diaphragm opposite the rod 72 with a tube 76 which leads, in the present instance, to the pipe 27 which, as above noted, is connected with the reservoir 33, thereby subjecting the diaphragm to the pressure in the reservoir and when this pressure reaches a predetermined pressure it will overcome the action of the spring 75 and move the plunger to a position to open the switch.

Means are also provided for venting the compressor after its operation has ceased so as to permit it to be subsequently started under no load and in the present instance this venting means is controlled by the pressure operated means which controls the switch so as to vent the compressor as soon as the switch is opened. For this purpose the pipe 27 is connected by a tube 77 with one end of a valve casing 78 (Figs. 4, 14 and 15), the other end of which is connected with the atmosphere, as by a tube 79 leading to the pipe 52 which is open to the atmosphere. Arranged within the valve casing 78 is a valve 80 which controls the connection between the tubes 77 and 79. In the arrangement shown this valve has a stem 81 which projects beyond the end of the valve casing and is arranged to be engaged and actuated by a lever 82 pivotally mounted at 83. This lever has an inclined surface 84 with which engages one end of a lever 85 pivotally mounted between its ends and having its other end connected by a link 86 with the switch lever 65, the arrangement being such that when the switch lever moves in a direction to open the switch the lever 85 will act on the inclined surface of the lever 82 and cause the latter to open the valve 80, thereby venting the pipe 27 and the compressor.

It is sometimes desirable to temporarily interrupt the operation of the lift in an intermediate position and this interruption may take place before the pressure in the air reservoir 33 has fallen sufficiently to start the compressor. When the movement of the lift is interrupted the main actuating device is restored to its neutral position, thereby closing the supply valve 35 and shifting the valve 49 to connect the valve chamber 48 with the interior of the main valve casing 29. At the time the interruption takes place the return valve 44 will be closed but the pressure in the work receptacle 24 will be transmitted through pipes 31 and 30 to the main valve casing and through the port 50 to the valve chamber 48.

and will act on the piston 46 of the actuating device for the return valve so as to open or partly open the return valve, thereby permitting air under pressure in the work receptacle to escape and be wasted. To prevent this I have provided the apparatus with means for preventing the opening of the return valve when the compressor is not in operation. When the compressor is in operation the discharge pipe 27 and the vent pipe 77 contain air under high pressure but when the compressor is idle the vent valve 80 is open and there is no substantial pressure in either the pipe 27 or the pipe 77. I have therefore interposed in the tube 47, which supplies air to the pressure operated device for the return valve, a cut-off valve which is normally closed and will be opened only when there is pressure in the vent pipe 77. This cut-off valve preferably comprises a casing 147 (Figs. 4 and 12) interposed in the tube 47 and having a valve seat 148 which is normally closed by a valve member 149 to prevent the flow of air from the valve chamber 48 to the pressure operated device for the return valve. This valve would ordinarily be held to its seat by pressure in that part of the tube 47 which is connected with the valve chamber 48 but I prefer to provide a spring 150 to insure the proper and prompt closing of the valve. The casing 147 is also provided with a cylinder 151 which is connected by a tube 152 with the vent pipe 77. Mounted in the cylinder 151 is a piston 153 which is connected with the valve member 149 and will be subjected to the pressure in the vent pipe 77 to actuate the piston and open the valve member 149. The piston is of such size that the pressure in the vent tube 77, when the compressor is in operation, will overcome the pressure of both the air and the spring on the valve member 149. Thus it will be apparent that if the movement of the lift is interrupted and the main actuating device returned to neutral position while the compressor is idle there will be no substantial pressure on the piston 153 and the supply of air to the pressure operated device for the return valve will be cut off but as soon as the compressor comes into operation pressure will be built up in the vent pipe 77 and the piston 153 actuated to open the cut-off valve and establish communication between the pressure operated device for the return valve and the valve chamber 48, thus placing said pressure operated device under the control of the valve 49 and enabling the return valve to be opened whenever the main actuating device is returned to its neutral position while the compressor is in operation.

The general arrangement of the apparatus is illustrated in Figs. 1 and 2 where the air reservoir 33 is shown as an upright cylindrical tank and the liquid or work receptacle 24 is shown as a cylindrical tank mounted alongside of the air reservoir and of a height substantially less than the height of the air reservoir. Preferably the two tanks are connected one to the other so as to constitute a unitary structure. The compressor 25 is mounted on the top of the work receptacle and is driven by a belt 81 from the motor 26 which is mounted on a bracket 88 rigidly secured to the upper portion of the air reservoir. If desired, the reservoir may be provided with a pressure gage 89. The main valve assembly including the valve casing 29 and the liquid valve, is mounted on the top of the work receptacle and the liquid pipe 23 extends downwardly therefrom and usually extends under-

ground to the lift cylinder. Preferably the mechanism which is mounted on the work receptacle is normally enclosed in a removable housing 90, with the exception of the main valve unit and its actuating device which are arranged exteriorly of the housing at the front of the apparatus with the actuating device conveniently located for operation.

Referring now to the specific construction of the various parts of the apparatus the preferred arrangement of the main valve unit is shown in Figs. 5 to 9 where the main valve casing 29 is illustrated as arranged in a horizontal position. The inlet valve 35 is mounted in a supplemental valve chamber 91 formed within the main casing 29 and the stem 36 of the valve 35 projects forwardly beyond the valve casing. Preferably a spring 92 is provided to insure the prompt seating of the valve when it is released by the actuating device. The supplemental chamber 54 for the exhaust valve 56 is arranged at the opposite end of the valve casing 29 and the exhaust valve 56 is mounted in the main chamber of the valve casing 29 and its stem 57 extends forwardly through the chamber 54 and beyond the front wall of the valve casing. This valve is also provided with a spring 92a to insure the prompt seating of the valve when the valve is released. The liquid valve 37 is mounted in a casing 93 inserted in and forming a part of the liquid conduit 23 and this casing 93 is, in the present instance, formed integral with the valve casing 29 and is arranged above the latter with the stem 38 of the valve 37 projecting forwardly from the front wall of the valve casing in a vertical plane arranged between the vertical planes of the stems 36 and 57 of the valves 35 and 56. In the present instance, the valve 37 is shown as a gate valve comprising two disk-like members 94 and 95 co-operating respectively with valve seats 96 and 97. These two members are connected one to the other by a ball and socket joint to enable the same to adjust themselves to the respective valve seats, the valve member 94 having a hub portion 98 provided with a socket 99 and the valve member 95 having a semi-spherical projection 100 extending into the socket 99. The valve stem 38 is provided with an annular portion 101 into which the hub 98 of the valve member 94 extends, thus providing a pivotal support for the valve as a whole. The valve stem 38 also has a guide portion 102 extending beyond the valve members into a closed guideway 103 and a spring 104 acts on the valve to hold the same normally in its closed position.

The actuating device 58 is here shown in the form of a metal plate or disk (see Fig. 16) having a hub portion 105 mounted for rocking movement on a stud 106 rigidly mounted in the front wall of the valve casing 29 and, in the present instance, arranged between and substantially in the horizontal plane of the valve stems 36 and 57, see Figs. 2 and 5. The cam surfaces 59 and 60, for actuating the supply valve 35 and exhaust valve 56, are formed just above and on opposite sides of the axis of the actuating member. The cam surfaces 61 and 62 for the liquid valve 37 are arranged above the cam surfaces 59 and 60. The several cam surfaces are so arranged that when the actuating member is in its central or neutral position the several valves will be released and will be retained in their closed positions. When the actuating member is moved in one direction, counterclockwise in Fig. 16, the cam surface 60 will engage the valve stem 36 and open the sup-

ply valve 35 and the cam 61 will engage the valve stem 38 and open the liquid valve 37. When the actuating member is restored to its initial position both valves will be released and will be automatically closed. The actuating member is provided with a handle 107 by means of which it may be manipulated and it may be restored to its neutral position either by manipulating the handle or by releasing the same and permitting it to be returned to neutral position by the action of the spring pressed valve stems on the cam surfaces. When the actuating member is moved in the opposite direction from its neutral position, that is, clockwise in Fig. 16, the cam surface 59 will engage the valve stem 57 and open the valve 56 and the cam surface 62 will engage the valve stem 38 and open the liquid valve 37.

The supplemental valve chamber 48 for the valve 49 which controls the supply of air to the actuating device of the return valve, is formed in the front wall of the valve casing 29 and, in the present instance, is located just below the stud 106 on which the actuating device is mounted. The port 50 connects the chamber 48 with the main chamber of the valve casing 29 and the port 51 connects the chamber 48 with the atmosphere. The valve 49 comprises two parts, a needle valve 108 to control the flow of air through the port 50 and a larger valve portion 109 to control the flow of air through the port 51. The valve is held normally in its open position by a spring 110, thus normally connecting the interior of the valve casing 29 with the pressure operated device which actuates the return valve. The stem 111 of the valve 48 extends beyond the front wall of the valve casing 29 and into a recess in the inner end of the hub 105 of the actuating device, the walls of this recess converging to form the cam surfaces 63 and 64 and both valve surfaces being out of engagement with the valve stem 111 when the actuating device is in its neutral position. Thus when the actuating device is moved in either direction from its neutral position the portion 108 of the valve 49 will close the port 50 to interrupt the supply of air to the pressure operated device, and the portion 109 will open the port 51 to vent the tube 47 and the pressure operated device. When the actuating device is returned to its neutral position the valve 49 will be automatically moved to its normal position by the spring 110.

The return valve unit, as shown in Figs. 12 and 13, comprises a valve casing 42 having a chamber 43 connected by the pipe 40 with the work receptacle and also having a chamber 112 which is connected by the pipe 41 with the intake of the compressor. The two chambers are separated by a partition provided with a port 113 which is controlled by a valve 44. The cylinder of the fluid pressure operated device which actuates the valve 44 is formed in a plug 114 screw threaded into an opening in the casing 42 in line with the port 43, and the piston 46 which is mounted in this cylinder is connected with the valve 44. In the present instance the piston is formed separately from the valve and is operatively connected therewith by contact of the piston with the collar 115 on the stem of the valve. The chamber 112 is provided with a port 116 leading to a chamber 117 which is connected by the pipe 52 with the atmosphere and is connected by the pipe 55 with the exhaust chamber 54 of the valve casing 29. The port 116 is controlled by the valve 53 which, in the arrangement here shown, is held in its open position by gravity.

The stem 119 of the valve 53 extends through a guideway 120 into a small chamber 121 formed in a plug 122 screw threaded into the lower portion of the valve casing 42. This chamber 121 is connected with a chamber 112 by a series of ports 123 so that air under pressure entering the chamber 112 will pass through the ports 123 into the chamber 121 and act on the lower end of the valve stem to close the valve.

The check valve 34 is interposed in the pipe 27 between the air reservoir 33 and the compressor and is preferably of the construction shown in Figs. 10 and 11, and, as there shown, is of such a type as to prevent chattering or vibration of the movable valve member. The valve casing comprises an outlet chamber 124 which is connected with the pipe 32 leading from the air reservoir, and with an inlet chamber 125 which is connected with that portion of the pipe 27 leading to the air compressor. The chambers 125 and 124 are connected by a port 126 provided with a valve seat 127. Arranged about and extending upwardly from the port 126 is a cylinder 128 which is held in tight engagement with the valve seat about the port by a cap 129 threaded into the upper part of the valve casing, and having a circumferential series of ports 130 near the lower end thereof. Mounted within the cylinder 128 is a piston like valve member 131 arranged to move by gravity to a position to close the port 126 and to be opened by air pressure in the chamber 125 so as to permit the air to pass through the ports 126 and 130 to the chamber 124 in the normal operation of the apparatus. The piston valve fits loosely in the cylinder and in the event of back pressure in the pipe 32 the air entering the chamber 24 will pass through the ports 130 and between the piston and the cylinder to the upper end of the cylinder where it will act on the piston to close the port 126. In the arrangement here shown the cylinder 128 is provided at each end with a series of ports 130 but the upper series of ports is inoperative and is provided merely to insure that in assembling the device the cylinder will be properly inserted in the valve casing.

Associated with the check valve 34 is a relief valve to vent the air reservoir in the event of excessive pressure therein. As shown it comprises a cylindrical valve chamber 132 formed in a lateral extension of the valve casing 34 and connected at its lower end with the valve chamber 124 by a port 133 and connected with the atmosphere by a port 134. Mounted within the chamber 132 is a piston like valve member 135 which normally engages a valve seat 136 surrounding the port 133 to close that port. The valve is held normally in its closed position by a spring 137 coiled about a valve stem 138. In the present instance the valve stem 138 is separate from the valve member 135 and is provided at its lower end with a rounded head 139 which is seated in a tapered recess 140 in the valve member to permit the valve member to adjust itself with relation to its valve seat, and the spring 137 is confined between the head 139 and the top wall of the chamber 132. The spring 137 is of sufficient strength to hold the valve in its closed position under normal operating pressure in the valve chamber 124 but in the event of excessive pressure in that chamber the valve member 135 will be moved against the action of the spring 137 to connect the chamber 124 with the atmosphere.

through the ports 133 and 134. The motor switch, its pressure controlled actuating mechanism and the relief valve 78 are mounted in a casing 141 supported on the upper end portion of the air reservoir 33.

The air which is stored under pressure in the reservoir 33 may be used not only for operating the lift but for various other purposes, such as operating a lubricating device, inflating tires and the like. The air reservoir is provided in its upper end with a valve controlled outlet 142 with which is connected a flexible hose 143 provided at its free end with a connector 144 whereby it may be attached to various fluid pressure operated devices. The organization of the present apparatus is such as to lend itself admirably to these other uses of the air. The assembly of the air reservoir and the work receptacle are such that they can be arranged at one side of a room, preferably against a wall, adjacent to the lift with which the apparatus is connected, and portable fluid operated devices arranged at the respective sides of the apparatus are shown at 145 in Fig. 1. These devices are provided with nipples 146 to receive the connector 144 and thus connect the same with the air reservoir. Thus the apparatus and its associated portable devices can be arranged in an orderly manner which not only facilitates their use but makes an attractive display of the various apparatus employed in the service station.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent is:

1. In an apparatus for utilizing the pressure energy of air to perform work including a work receptacle in which air is retained under pressure after work has been performed, an air compressor, a valve casing, conduits to connect said valve casing with said compressor and said work receptacle, a supply valve in said casing to control the flow of air thereto from said compressor, a return conduit for connecting said work receptacle with the intake of said compressor, a return valve in said return conduit arranged to be held closed by pressure in said return conduit, a fluid pressure operated device to open said return valve, means for connecting said pressure operated device with said casing between said supply valve and the conduit leading to said work receptacle and including a valve to control said connection, means including an actuating device to open said supply valve and close said controlling valve when said actuating device is moved in one direction and to close said supply valve and open said controlling valve to transmit the pressure from said work receptacle to said pressure operated device when said actuating device is moved in another direction, and means for supplying air to the intake of said compressor when said return valve is closed.

2. In an apparatus comprising a hydraulic lift, a receptacle for liquid having an air space above the liquid therein, a conduit for liquid leading from said receptacle to said lift, a valve to control the passage of liquid through said conduit, an air compressor, a conduit to supply air under pressure from said compressor to the air space in said receptacle, a valve to control the passage of air through said supply conduit, a re-

turn conduit to connect the air space in said receptacle with the intake of said compressor, a valve to control the passage of air through said return conduit, fluid pressure operated means for

5 actuating said return valve, means for connecting said pressure operated device with a source of supply of air under pressure, a valve for controlling said connection, means including an actuating device for opening said supply and liquid valves and closing the last mentioned valve when one movement is imparted to said actuating device, and for closing said supply and liquid valves, retaining the same closed to prevent the lowering of said lift and opening said last mentioned valve when another movement is imparted to said actuating device, and means for supplying air to said compressor while said return valve is closed.

3. In an apparatus comprising a hydraulic lift, a receptacle for liquid having an air space

20 above the liquid therein, a conduit for liquid leading from said receptacle to said lift, a normally closed valve to control the flow of liquid through said conduit, an air compressor, a conduit to supply air under pressure from said compressor to the air space in said receptacle, a normally closed valve to control the flow of air through said supply conduit, a return conduit to connect the air space in said receptacle with the intake of said compressor, a valve to control the flow of air

25 through said return conduit, fluid pressure operated means for actuating said return valve, an actuating device movable in one direction from a neutral position to open said supply and liquid valves and movable in another direction from said neutral position to open said liquid valve while said supply valve is closed, and means controlled by said actuating device to connect said pressure operated means with a source of supply for air under pressure for opening said return valve when

40 said actuating device is in said neutral position and to interrupt said connection when said actuating device is moved in either direction from said neutral position, and means for supplying air to said compressor when said return valve is closed.

45 4. In an apparatus including a hydraulic lift, a liquid receptacle having an air space above the liquid therein, a liquid conduit to connect said receptacle with said lift, a valve to control the flow of liquid through said conduit, an air com-

50 pressor, means including a valve to supply air under pressure from said compressor to said receptacle, a conduit for returning air under pressure from said receptacle to the intake of said compressor, a return valve in said return conduit,

55 an actuating device, means controlled by said actuating device for closing said air supply valve, closing said liquid valve to retain said lift in an elevated position and opening said return valve to return air under pressure from said receptacle to said compressor while said lift is retained in said elevated position, and means for supplying air to said compressor while said return valve is closed.

60 5. In an apparatus including a hydraulic lift, a liquid receptacle having an air space above the liquid therein, a liquid conduit to connect said receptacle with said lift, a valve to control the flow of liquid through said conduit, an air com-

70 pressor, means including a valve to supply air under pressure from said compressor to said receptacle, a conduit for returning air under pressure from said receptacle to the intake of said compressor, a return valve in said return conduit, an actuating device, means controlled by the successive movements of said actuating device for

opening said supply and liquid valves to elevate said lift and closing said return valve and retaining the same closed during the elevation of said lift, for closing said supply and liquid valves and opening said return valve to retain said lift in an elevated position and return the air under pressure from said receptacle to said compressor while said lift is so retained in said position, and for opening said liquid valve to lower said lift, and means for supplying air to said compressor while said return valve is so closed.

6. In an apparatus including a hydraulic lift, a liquid receptacle having an air space above the liquid therein, a liquid conduit to connect said receptacle with said lift, a valve to control the flow of liquid through said conduit, an air compressor, means including a valve to supply air under pressure from said compressor to said receptacle, a conduit for returning air under pressure from said receptacle to the intake of said compressor, a return valve in said return conduit, an actuating device, means controlled by said actuating device for closing said air supply valve, closing said liquid valve to retain said lift in an elevated position and opening said return valve to return air under pressure from said receptacle to said compressor while said lift is retained in said elevated position, means controlled by said actuating device to exhaust air from said receptacle while said return valve is closed, and means for supplying air to said compressor while said return valve is closed.

7. In a fluid operated apparatus, a closed liquid receptacle having an air space above the liquid therein, means for conducting liquid under pressure from said receptacle to a device to be operated, an air compressor, means for supplying air under pressure from said compressor to the air space in said receptacle, a return conduit to deliver air under pressure from said receptacle to the intake of said compressor, a return valve to control the flow of air through said return conduit, means including an actuating device for interrupting the supply of air from said compressor to said receptacle and for opening said return valve, means separate from said return valve and controlled by said actuating device for exhausting air from said receptacle while the supply of air thereto is interrupted, and means for supplying air to the intake of said compressor while said return valve is closed.

8. In a fluid operated apparatus, a closed liquid receptacle having an air space above the liquid therein, means for conducting liquid under pressure from said receptacle to a device to be operated, an air compressor, means including a valve for supplying air under pressure from said compressor to said receptacle, a conduit for returning air under pressure from said receptacle to the intake of said compressor, a return valve to control the flow of air through said return conduit, means including a valve to exhaust air from said receptacle independently of said return valve, an actuating device having means operable upon successive movements thereof to first open said supply valve and close said return valve, to then close said supply valve and open said return valve and to thereafter open said exhaust valve, and means for supplying air to said compressor while said return valve is closed.

9. In a fluid operated apparatus, a hydraulic lift, a closed liquid receptacle having an air space above the liquid therein, a liquid conduit connecting said receptacle with said lift, a valve to control the flow of liquid through said conduit,

an air compressor, means including a valve for supplying air under pressure from said compressor to said receptacle, a conduit for returning air under pressure from said receptacle to the intake of said compressor, a return valve to control the flow of air through said return conduit, means other than said return conduit and including a valve to exhaust air from said receptacle, an actuating device having means operable upon successive movements thereof to first open said supply and liquid valves and close said return valve, to then close said supply and liquid valves and open said return valve and to thereafter open said liquid and exhaust valves, and means for supplying air to said compressor while said return valve is closed.

10. In a fluid operated apparatus, a hydraulic lift, a closed liquid receptacle having an air space above the liquid therein, a liquid conduit connecting said receptacle with said lift, a valve to control the flow of liquid through said conduit, an air compressor, means including a valve for supplying air under pressure from said compressor to said receptacle, a conduit for returning air under pressure from said receptacle to the intake of said compressor, a return valve to control the flow of air through said return conduit, a fluid operated device to open said return valve, means including a control valve to connect said fluid operated device with said air supply means, means including an exhaust valve for exhausting air from said receptacle independently of said return valve, an actuating device having means operable on successive movements thereof to first open said supply and liquid valves and close said control valve, to then close said supply and liquid valves and open said control valve and to thereafter open said exhaust and liquid valves, and means to supply air to said compressor while said return valve is closed.

11. In an apparatus comprising a hydraulic lift, a receptacle for liquid having an air space above the liquid therein, a conduit for liquid leading from said receptacle to said lift, a valve to control the passage of liquid through said conduit, an air compressor, a conduit to supply air under pressure from said compressor to the air space in said receptacle, a valve to control the passage of air through said supply conduit, a return conduit to connect the air space in said receptacle with the intake of said compressor, a valve to control the passage of air through said return conduit, fluid pressure operated means for opening said return valve, means including a valve for connecting said pressure operated means with a source of supply of air under pressure, means for venting said liquid receptacle while said return valve is closed, an actuating device having means for opening said liquid and supply valves and for closing said connecting valve when moved in one direction from its normal position, and for opening said liquid valve, actuating said venting means and closing said connecting valve when moved in another direction from its normal position, and means for supplying air to said compressor while said return valve is closed.

12. In an apparatus comprising a hydraulic lift, a receptacle for liquid having an air space above the liquid therein, a conduit for liquid leading from said receptacle to said lift, a valve to control the passage of liquid through said conduit, an air compressor, a conduit to supply air under pressure from said compressor to the air space in said receptacle, a valve to control the

passage of air through said supply conduit, a return conduit to connect the air space in said receptacle with the intake of said compressor, a valve to control the passage of air through said return conduit, means including an exhaust valve to vent said work receptacle, a single actuating device having means for controlling the positions of said supply valve, said exhaust valve, said liquid valve and said return valve.

13. In an apparatus comprising a hydraulic lift, a receptacle for liquid having an air space above the liquid therein, a conduit for liquid leading from said receptacle to said lift, a valve to control the passage of liquid through said conduit, an air compressor, a conduit to supply air under pressure from said compressor to the air space in said receptacle, a valve to control the passage of air through said supply conduit, a return conduit to connect the air space in said receptacle with the intake of said compressor, a valve to control the passage of air through said return conduit, fluid pressure operated means for actuating said return valve, means for connecting said pressure operated device with a source of supply of air under pressure, a valve for controlling said connection, means including a valve for exhausting air from said receptacle, means including an actuating device movable in two directions from a neutral position for opening said supply valve and said liquid valve and for closing the controlling valve for said pressure operated device when said actuating device is moved in one direction from said neutral position, for closing said supply and liquid valves, and opening said control valve when said actuating device is returned to its neutral position, and for opening said exhaust valve and said liquid valve when said actuating device is moved in the other direction from its neutral position, and means for supplying air to said compressor while said return valve is closed.

14. In an apparatus comprising a hydraulic lift, a receptacle for liquid, an air compressor, means including a normally closed valve for supplying air from said compressor to said liquid receptacle, means including a normally closed valve for delivering liquid from said receptacle to said lift, means including a return valve for connecting the air space of said receptacle with the intake of said compressor, means including a normally closed valve for exhausting air from said receptacle while said return valve is closed, fluid pressure operated means for actuating said return valve, a normally open valve to connect said fluid pressure operated means with a source of air supply, an actuating device movable in either of two directions from a neutral position and having means for opening said supply valve and said liquid valve and for closing said controlling valve when said actuating device is moved in one direction from said neutral position, and for opening said exhaust valve and said liquid valve when said actuating device is moved in another direction from said neutral position, and means for supplying air to said compressor while said return valve is closed.

15. In an apparatus of the character described, a work receptacle, an air compressor, means for supplying air under pressure from said compressor to said work receptacle including a valve casing and pipes connecting said valve casing with said compressor and with said work receptacle, a supply valve in said valve casing, an exhaust pipe connected with said valve casing, an exhaust valve in said valve casing, a return con-

duit connecting said work receptacle with the intake of said compressor, pressure operated means for controlling the flow of air through said return conduit, means including a valve in said valve casing for connecting said pressure operated means with the air supply portion of said valve casing, and a single actuating device having means for controlling the position of each of the three valves in said valve casing.

16. In an apparatus for utilizing the pressure energy of air to perform work, including a work receptacle in which air is retained under pressure after work has been performed, an air compressor, and means including a valve for supplying air under pressure from said compressor to said work receptacle; a return conduit for connecting said work receptacle with the intake of said compressor, a valve in said return conduit, means for actuating said return valve, means controlled by said compressor to prevent the opening of said return valve when said compressor is not operating, means for actuating said supply valve, and means for supplying air to said compressor while said return valve is closed.

17. In an apparatus for utilizing the pressure energy of air to perform work, including a work receptacle in which air is retained under pressure after work has been performed, an air compressor, and means including a valve for supplying air under pressure from said compressor to said work receptacle; a return conduit for connecting said work receptacle with the intake of said compressor, a valve in said return conduit, a fluid pressure operated device for actuating said return valve, means for connecting said pressure operated device with a source of air under pressure, means controlled by said compressor to interrupt the connection between said pressure operated device and said air source when said compressor is idle, means for actuating said supply valve, and means for supplying air to said compressor while said return valve is closed.

18. In an apparatus for utilizing the pressure energy of air to perform work, including a work receptacle in which air is retained under pressure after work has been performed, an air compressor, and means including a valve for supplying air under pressure from said compressor to said work receptacle; a return conduit for connecting said work receptacle with the intake of said compressor, a valve in said return conduit, a fluid pressure operated device for actuating said return valve, means for connecting said pressure operated device with a source of air under pressure and including a valve to control said connection, an actuating device having means to control the operation of said supply valve and said controlling valve, a cut-off valve interposed between said pressure operated device and said controlling valve, means controlled by said compressor for actuating said cut-off valve, and means for supplying air to said compressor while said return valve is closed.

19. In an apparatus for utilizing the pressure energy of air to perform work, including a work receptacle in which air is retained under pressure after work has been performed, an air compressor, and means including a valve for supplying air under pressure from said compressor to said work receptacle; a return conduit for connecting said work receptacle with the intake of said compressor, a valve in said return conduit, a fluid pressure operated device for actuating said return valve, means for connecting said pressure

operated device with a source of air under pressure, a normally closed cut-off valve interposed between said pressure operated device and said air source, pressure operated means for opening said cut-off valve, means for connecting the last mentioned pressure operated means with the outlet of said compressor to cause said cut-off valve to be opened when said compressor is in operation, means for actuating said supply valve, and means for supplying air to said compressor while said return valve is closed.

20. In an apparatus including a hydraulic lift, a liquid receptacle having an air space above the liquid therein, an air compressor, means for supplying air under pressure from said compressor to said receptacle, means for connecting said receptacle with said lift to deliver liquid under pressure from said receptacle to said lift to elevate the latter and for interrupting said connection to hold said lift against downward movement, means for returning air under pressure from said receptacle to the intake of said compressor while said lift is held against downward movement, and means for supplying air to said compressor while said return means is inoperative.

21. In an apparatus including a hydraulic lift, a liquid receptacle having an air space above the liquid therein, an air compressor, means for supplying air under pressure from said compressor to said receptacle, means for connecting said receptacle with said lift to deliver liquid under pressure from said receptacle to said lift to elevate the latter and for interrupting said connection to hold said lift against downward movement, a conduit for returning air under pressure from said receptacle to the intake of said compressor, a valve in said conduit arranged to be held closed by the pressure of air in said receptacle, a fluid operated device to open said valve, means for supplying air under pressure to said pressure operated device to open said valve and return air under pressure from said receptacle to said compressor while said lift is held against downward movement, and means for supplying air to said compressor while said valve is closed.

22. In an apparatus including a hydraulic lift, a liquid receptacle having an air space above the liquid therein, a liquid conduit connecting said receptacle with said lift, a valve in said conduit, an air compressor, a conduit to supply air under pressure from said compressor to the air space in said receptacle and thus deliver liquid under pressure to said lift, a supply valve to control the flow of air through said supply conduit, a return conduit leading from the air space in said receptacle to the intake of said compressor, a return valve in said return conduit arranged to be held in its closed position when said supply valve is open, means including a valve to exhaust air from said receptacle while said lift is being lowered and said return valve is closed, and means for supplying air to said compressor while said return valve is closed.

23. In an apparatus including a hydraulic lift, a liquid receptacle having an air space above the liquid therein, a liquid conduit connecting said receptacle with said lift, an air compressor, a conduit to supply air under pressure from said compressor to the air space in said receptacle and thus deliver liquid under pressure to said lift, a supply valve to control the flow of air through said supply conduit, a return conduit leading from the air space in said receptacle to the intake

of said compressor, a return valve in said return conduit arranged to be held in its closed position when said supply valve is open, means including a valve to exhaust air from said receptacle while said lift is being lowered and said return valve is closed, a valve in said liquid conduit, means for opening said return valve while said liquid valve is closed to retain said lift in an elevated position, and means for supplying air to said compressor while said return valve is closed.

24. In a fluid operated lifting mechanism, a hydraulic lift, a liquid receptacle having an air space above the liquid therein, a liquid conduit connecting said receptacle with said lift, an air compressor, a conduit to supply air under pressure from said compressor to the air space in said receptacle and thus deliver liquid under pressure to said lift, a supply valve to control the flow of air through said supply conduit, a return conduit leading from the air space in said receptacle to the intake of said compressor, a return valve in said return conduit arranged to be held in its closed position when said supply valve is open, a liquid valve to prevent the return of liquid from said lift to said receptacle, means for opening said return valve while said supply and liquid valves are closed to permit air under pressure to flow from said receptacle to said compressor, and means for supplying air to said compressor while said return valve is closed.

25. In a fluid operated lifting mechanism, a hydraulic lift, a liquid receptacle having an air space above the liquid therein, a liquid conduit connecting said receptacle with said lift, an air compressor, a conduit to supply air under pressure from said compressor to the air space in said receptacle and thus deliver liquid under pressure to said lift, a supply valve to control the flow of air through said supply conduit, a return conduit leading from the air space in said receptacle to the intake of said compressor, a return valve in said return conduit arranged to be held in its closed position when said supply valve is open, a liquid valve to prevent the return of liquid from said lift to said receptacle, means for opening said return valve while said supply and liquid valves are closed to permit air under pressure to flow from said receptacle to said compressor, and means for exhausting air from said receptacle while said supply valve is closed and said liquid valve is open to permit said liquid to flow from said lift to said receptacle.

26. In a fluid operated lifting mechanism, a hydraulic lift, a liquid receptacle having an air space above the liquid therein, a liquid conduit connecting said receptacle with said lift, an air compressor, a conduit to supply air under pressure from said compressor to the air space in said receptacle and thus deliver liquid under pressure to said lift, a supply valve to control the flow of air through said supply conduit, a return conduit leading from the air space in said receptacle to the intake of said compressor, a return valve in said return conduit arranged to be held in its closed position when said supply valve is open, a fluid pressure operated device to open said return valve, a liquid valve to prevent the return of liquid from said lift to said receptacle, and means for supplying air under pressure to said pressure operated device while said supply and liquid valves are closed to open said return valve and permit air under pressure to flow from said receptacle to said compressor,

and means for supplying air to said compressor while said return valve is closed.

27. In a fluid operated lifting mechanism, a hydraulic lift, a liquid receptacle having an air space above the liquid therein, a liquid conduit connecting said receptacle with said lift, an air compressor, a conduit to supply air under pressure from said compressor to the air space in said receptacle and thus deliver liquid under pressure to said lift, a supply valve to control the flow of air through said supply conduit, a return conduit leading from the air space in said receptacle to the intake of said compressor, a return valve in said return conduit arranged to be held in its closed position when said supply valve is open, a fluid pressure operated device to open said return valve, a liquid valve to prevent the return of liquid from said lift to said receptacle, means for supplying air under pressure to said pressure operated device while said supply and liquid valves are closed, means for exhausting air from said receptacle while said liquid valve is open and liquid is flowing from said lift into said receptacle, and means for supplying air to said compressor while said return valve is closed.

28. In a fluid operated lifting mechanism, a hydraulic lift, a liquid receptacle having an air space above the liquid therein, a liquid conduit connecting said receptacle with said lift, a valve to control the flow of liquid through said liquid conduit, a conduit to supply air under pressure from said compressor to the air space in said receptacle, a normally closed supply valve in said supply conduit, an exhaust conduit connected with said supply conduit between said supply valve and said receptacle, a normally closed valve in said exhaust conduit, means for separately opening said supply and exhaust valves, a return conduit leading from the air space in said receptacle to the intake of said compressor, a return valve in said return conduit arranged to be held closed by air pressure when said supply valve is open, means for opening said return valve while said supply and exhaust valves are closed to permit air under pressure to flow from said receptacle to said compressor, and means for supplying air to said compressor while said return valve is closed.
